UNITED STATES PATENT OFFICE.

FREDERICK COCKER, OF DANBURY, CONNECTICUT, AND GEORGE YULE, OF NEWARK, NEW JERSEY, ASSIGNEES TO THE HAT-CURLING MACHINE COMPANY, OF DANBURY, CONNECTICUT.

HAT-CURLING MACHINE.

SPECIFICATION forming part of Letters Patent No. 320,115, dated June 16, 1885.

Application filed March 23, 1885. (No model.)

To all whom it may concern:

Be it known that we, FREDERICK COCKER, a subject of the Queen of Great Britain, and GEO. YULE, a citizen of the United States, residing, respectively, in Danbury and Newark, counties of Fairfield and Essex, and States of Connecticut and New Jersey, have invented certain new and useful Improvements in Hat-Curling Machines, fully described and represented in the following specification and the accompanying drawings, forming a part of the same.

This invention consists, first, in an adjustable gage to assist the breaker in first bending the edge of the hat-brim at the desired point; and, secondly, in a separator to prevent the contact of the curled felt with the "under brim" beneath it. Our improvements are adapted especially for the production of flat, angular, or so-called "Anglesea" curls, in which the edge of the brim requires pressing first into a close flat fold before it can be made to retain the open angular form desired, and in the formation of which the edge of the folded felt is liable to mark or compress the body of the hat-brim if pressed down hard upon it, as has been common heretofore.

Our separator consists in a thin slip of metal held between the pressing-iron and the brim-supporting plate, and, being inserted between the hat-brim and the fold of the curl, it not only prevents the marking of the under brim and the sticking of the two together, as often happens without its use, but it furnishes a much harder surface upon which to press the curl than is afforded by the felt of the under brim, and thereby effects the pressing or ironing of the curl in a much more rapid and effective manner.

It has been common heretofore to shape and form the curl by applying a guide-plate or former to the upper side of the brim and then bending the edge of the brim over said former by means of a cloth, a heated bag, or metallic segments; but our separator, as will be fully shown herein, differs from such a guide-plate in not fitting the brim at all points, in not aiding in any manner to determine the final shape of the curl, and in operating merely to

prevent the curl from being pressed into or 50 upon the under brim and thereby sticking to or deforming the latter. Such guide-plates as we have just referred to are necessarily fitted to the entire shape of the hat-curl, and require to be changed or altered for any change 55 in the required shape of the curl, and, as the hat and guide-plate are both stationary, the curl cannot be formed at all without the use of the latter. Upon the contrary, the mechanism with which we use our separator—namely, the 60 rotating brim-plate and vibrating curling-iron or presser—are fully adapted to produce and finish the curl without the intervention of the separator, and the latter is inserted within the curl neither to produce or finish the same, but 65 to protect the under brim, as described herein. We therefore disclaim a guide-plate inserted within the curl to aid in determining the shape of the latter, as the separator described herein is not intended to exercise any 70 such function.

Our improved gage operates, in conjunction with the breaker, to turn over or "break" the edge of the hat-brim during the first revolutions of the latter in the curling-machine, the 75 breaking or curling iron being retracted during such primary breaking operation.

Our invention will be understood by reference to the annexed drawings, in which Figure 1 is a side elevation of a hat-curling machine 80 provided with our improvements, the parts at the left side of the machine being shown in section on line *x* *x* in Fig. 2, excepting the hat-clamp. Fig. 2 is a plan of the machine, with the parts above line *y* *y* at the left side 85 of Fig. 1 omitted, to show the breaker-gage more clearly. Fig. 3 is an elevation of the left end of the same machine, showing the means of adjusting the carrier and breaker-gage. Fig. 4 is a view of the inner end of the 90 iron, the breaker, and the separator, of their natural size, with a portion of the hat-brim, the latter being shown in section on line *x* *x*, in Fig. 5, which view shows the same parts in plan, the iron being shown only in dotted lines 95 to avoid obscuring the other parts of the figure, which includes a portion of the hat-brim and crown, the curl being shown in both

In Figs. 3 and 4 the fold *f* is shown entering the mouth of the iron at *g'*, passing over the highest point of the breaker at line *b b*, and pressed closely toward the under brim at the heel of the iron, on line *c c*, the iron being shaped, as is usual, to first plow or bend the curl up, as shown in Fig. 5, to then fold it over the breaker, as in Fig. 6, and to finally press it down flat, as shown in Fig. 7. In the formation of Anglesea curls, such as are shown in Fig. 6, and others in which the felt is folded closely and sharply down around the edge of the hat-brim, great difficulty has been experienced heretofore in pressing the fold down upon the under brim with sufficient pressure to bend the fold permanently to the required shape without forcing the fold partially into the under brim, and without occasionally sticking the fold to the brim when the shellac "stiffening" was heated by the pressing-iron. As 15 curls of this character are always formed by first pressing the felt down flat, as shown in Fig. 8, it is obvious that when the fold rests upon the under brim the pressure must affect 20 one part of the felt just as much as the other, so that when the fold is afterward finished by lifting it to the position shown in Fig. 7, the under brim is distinctly marked or compressed where the edge of the fold lay upon it.

In Figs. 4 and 8 our separator is distinctly shown inserted between the fold and the brim, and effectually preventing both the marking of the brim just referred to and the sticking of the fold to the same at any stage of the 25 curling operation. The construction for this purpose obviously consists of a thin plate sustained independently of the iron in such manner as to project beneath the heel of the iron at *h'*, so that the separator will lie under 30 the fold and separate the same from the brim beneath; and it is therefore immaterial whether the separator be attached to the breaker or formed apart from the breaker and otherwise supported. relation to the others or to the hat-clamp by means of the adjustable connection between the roller d^2 and the holder itself.

5 The breaker-gage, the iron, and the breaker may also be operated in any other manner than that shown herein, although we have found it preferable to set the gage before or in front of the iron h , and to partially break the curl with the gage and breaker prior to the operation of the iron h .

10 Having thus set forth the nature of our invention, we claim and desire to secure the same in the following manner:

15 1. In a hat-curling machine, the combination, with a rotary plate and hat-brim supported thereon, of a curling-iron, adapted to fold or press the hat-brim upon the plate, and a flat separator inserted within the fold of the rotating curl, and operating to keep the curl 20 from contact with the under brim, substantially as herein shown and described.

25 2. In a hat-curling machine, the combination, with the curling-iron and breaker, operating together as described, of a flat separator attached to the breaker, as and for the purpose set forth.

30 3. In a hat-curling machine, the combination, with a breaker, adapted to form a flat or Anglesea curl, and an iron beveled to fit the breaker and flattened at the heel to fold down the curl, as described, of a flat separator attached to the breaker and extended under the heel of the iron, as and for the purpose set forth.

35 4. In a hat-curling machine, the combination, with a vibrating holder, of a tool-carrier and a hinged breaker separately secured thereon, a breaker-gage attached to the tool-holder, and means for adjusting the gage in relation 40 to the holder, as and for the purpose set forth.

45 5. In a hat-curling machine, the combination, with a vibrating holder, of a tool-carrier and a hinged breaker separately secured thereon, a breaker-gage attached to the tool-holder,

and means for adjusting the breaker and the 45 gage separately in relation to one another and to the holder, as and for the purpose set forth.

6. In a hat-curling machine, the combination, with a vibrating holder, of a tool-carrier and breaker separately secured thereon, a 50 curling-iron provided with a notch to admit a breaker-gage, and a gage adjustably secured to the holder and projected through the notch in the lower side of the iron, to operate with the breaker before the iron, as and for the 55 purpose set forth.

7. In a hat-curling machine, the combination, with a curling-iron and the rotary plate supporting the hat-brim, of a holder having a tool-carrier, a breaker, and a breaker-gage, 60 each adjustably attached thereto, and a flat separator combined with the rear edge of the breaker, as and for the purpose set forth.

8. In a hat-curling machine, the combination, with a rotary brim-plate and hat-clamp, 65 of two vibrating holders, one holder being provided with a brim-bending tool, a hinged breaker, a separator, and an adjustable breaker-gage, arranged and operated as described, and the other holder being provided with a 70 flattening-iron and a separator, the whole arranged and operated as and for the purpose set forth.

9. In a hat-curling machine, the combination, with a vibrating holder, of a tool-carrier, a 75 hinged breaker, and a breaker-gage, with means for adjusting the carrier, breaker, and breaker-gage separately, as and for the purpose set forth.

10. In testimony whereof we have hereunto set 80 our hands in the presence of two subscribing witnesses.
